UNITED STATES PATENT OFFICE.

CHARLES H. ATKINS, OF PALMER, MASSACHUSETTS, ASSIGNOR TO ATKINS AND COMPANY, INC., OF PALMER, MASSACHUSETTS, A CORPORATION OF MASSACHUSETTS.

PACKING BOX FOR SIPHON PIPES.

Application filed November 28, 1925. Serial No. 71,969.

My invention relates to improvements in packing boxes more especially for use in connection with siphon pipes employed for carrying off air and the water of condensation from the interiors of drying cylinders or drums, such as are commonly used in textile, paper, and other mills, and resides particularly in a spiral spring encircling a siphon pipe within a tubular case, and introduced between a follower and an adjusting sleeve or plug mounted on said pipe, said plug being held in place at the outer end by means of a screw-cap on said case, all substantially as hereinafter set forth in greater detail.

The siphon pipes, to which my invention applies, pass through hollow bearing boxes, and the primary object of said invention is to provide such a bearing box with a packing box equipped with means to produce a yielding tension on the compression member or follower for the packing, to the end that said follower is self-adjusting, and any wear or change in the condition of said packing is compensated for, without requirement for frequent adjustment of the pressure means. In the old type of packing box, manual adjustment of the follower is frequently required, frequently as often as once a day, while in the present construction manual adjustment may not be needed oftener than once a month.

This packing box is simple in construction, convenient to install, and can be easily and quickly removed in the event it becomes necessary for any reason to obtain access to the interior thereof, or to the packing against which the follower is normally held, or to remove the siphon pipe which extends through said box.

This device affords means for making a steam and water-tight joint between the cylinder shaft and bearing.

Other objects and advantages will appear in the course of the following description.

I attain the objects and secure the advantages of my invention by the means illustrated in the accompanying drawings, in which—

Figure 1 is a longitudinal, vertical section through a packing box for siphon pipes, which embodies a practical form of my invention, and, Fig. 2, a side elevation of a drying cylinder and associated parts and

members, illustrating the application thereto of said invention, this view being on a smaller scale than the first view.

Similar reference characters designate similar parts throughout the several views.

In the drawings, a portion of a drying cylinder or drum is represented at 1, a portion of a hollow shaft therefor at 2, a spur gear at 3 for driving said shaft and drum, a hollow bearing box at 4, a discharge or siphon pipe at 5, and a follower at 6. Steam under pressure is introduced into the bearing box 4, and passes therefrom into the drum 1 through the hollow shaft 2. The diameter of the siphon pipe 5 is smaller than that of the passage through the shaft 2, and said pipe is bent downwardly within the drum 1 until the inner end of said pipe is quite close to the lower side of said drum. The pipe 5 after leaving the hollow shaft 2 passes outwardly beyond the hollow bearing 4, and the follower 6 is mounted on said pipe in position to bear against packing 7 which surrounds the outer terminal of said shaft, such terminal protruding from that portion of said bearing which directly supports the shaft into an enlarged chamber in said bearing. The follower 6 consists in part of a ring 8 which enters an annular space provided between the shaft 2 and the bearing box 4 to receive the packing 7, and is for the purpose of forcing said packing tightly against said shaft to prevent leakage of steam and water between said shaft and box. It is this joint that my invention is designed to keep tight at all times. The siphon pipe 5 is for the purpose of permitting the confined air and the water of condensation in the drum 1 to be driven therefrom by the incoming steam.

The parts and members thus far described, both structurally and functionally, are old and well known.

The bearing box 4 is provided at the outer end with an interiorly screw-threaded flange 9, and a tubular member or case 10 is provided at one end with an enlarged head 11 which is adapted to fit into said flange, said head being exteriorly screw-threaded to engage the screw-threads on the flange. The tubular case 10 is externally screw-threaded at the outer terminal to receive a screw cap 12. Located partly in the case 10 and part-

ly in the cap 12 is a hollow adjusting plug or follower 13. The follower 13 has at the outer end a head 14 which prevents said follower from being forced completely into the case 10. The pipe 5 extends through the case 10 and the follower 13 and out through the outer end of the cap 12, and a spiral spring 15 is mounted on said pipe between said follower and the follower 6, there preferably being a pair of packing-rings 16 and a metallic washer 16^a introduced between the adjacent ends of said first-named follower and said spring. A portion of the spring 15 is in the case 10 and another portion thereof in the hollow bearing 4, and the packing-ring 16 and washer 16^a are in said case, said washer being next to said spring.

It is now evident that the spring 15, which is always under compression from the follower 13 and the screw cap 12, exerts a yielding pressure on the follower 6, and forces the latter tightly against the packing 7, with the result that said packing is forced against the joint between the shaft 2 and the box 4. Since such pressure is yielding, the follower 6 automatically adjusts itself to the packing 7, and there is provided automatic compensation for wear or other change in the condition of said packing. Occasionally, as the contacting and rubbing parts wear, the cap 12 is screwed farther onto the case 10, and, thereby, through the medium of the follower 13 and the intervening packing-rings 16 and washer 16^a, increases the compression of the spring 15, thus causing the follower ring 8 to be forced tighter or harder against the packing 7.

The screw cap 12, with the associated parts and members, besides affording means for increasing the pressure of the spring 15, also enables said spring initially to be compressed to just the extent required, and to be

maintained under the desired degree of compression.

The removal of the pipe 5 and the follower 6 from the drum 1 and the bearing box 4 is easily effected merely by unscrewing the head 11 of the case 10 from the flange 9 of said box.

It is understood, of course, that the drum 50 1 revolves with its shaft 2, but that the pipe 5 is stationary.

More or less change in matters of detail may be made in this device without departing from the spirit of my invention or exceeding the scope of what is claimed.

What I claim as my invention, and desire to secure by Letters Patent, is—

The combination, in a packing box of the class described, with a drum mounted on a hollow shaft, a bearing box for said shaft, said box having a screw-threaded flange at the outer end, a siphon pipe of less diameter than the shaft passage and extending through said passage, packing on said shaft 60 in said bearing box, and a follower mounted on said pipe in position to compress said packing, of a case encircling said pipe and provided with a screw-threaded head to engage said flange, a screw cap mounted on 65 the outer terminal of said case, through which cap said pipe extends, a follower mounted on said pipe partially within said case and partially within said cap, in position to be moved inwardly by said cap, and having an enlarged head at the outer end to prevent such end from entering said case, a spring extending from the inner end of 70 said second-named follower in said case to said first-named follower in said bearing 75 box, and a packing-ring and a washer mounted on said pipe between adjacent ends of said second-named follower and spring.

CHARLES H. ATKINS.
